EXCAVATOR

Samuel M. Highberger and Harlan E. Kifer, Birmingham,
Mich., assignors to Massey-Ferguson Inc., Detroit,
Mich.

Filed Jan. 18, 1967, Ser. No. 5,466

Term of patent 14 years

(Cl. D14—3)

Fig. 1

Fig. 2

Fig. 3

Fig. 4

FIGURE 1 is a perspective view of an excavator embodying our new design; and taken generally from the left rear thereof.

FIGURE 2 is a perspective view of the excavator taken from the right rear thereof.

FIGURE 3 is a front elevational view of the excavator.

FIGURE 4 is a perspective view of the excavator taken generally from the right rear side looking down at the excavator.

The dominant features of the design reside in the portion shown in full lines, and it is to be understood that the fragmentarily disclosed mesh material continues throughout the designated areas.

We claim:

The ornamental design for an excavator, substantially as shown and described.
